UNITED STATES PATENT OFFICE.

HENRY C. MARX, OF PALMER, KANSAS, ASSIGNOR TO THE PHONOHARP COMPANY,
OF EAST BOSTON, MASSACHUSETTS, A CORPORATION OF MAINE.

KEYED ZITHER.

1,150,285.

Specification of Letters Patent.

Patented Aug. 17, 1915.

Application filed August 28, 1913, Serial No. 787,157. Renewed January 2, 1915. Serial No. 255.

To all whom it may concern:

Be it known that I, HENRY C. MARX, a citizen of the United States, and a resident of Palmer, in the county of Washington and

5 State of Kansas, have invented certain new and useful Improvements in Keyed Zithers, (Case A,) of which the following is a specification.

This invention has relation to musical instruments, and more particularly to means 10 for playing the same.

In Letters Patent No. 1,044,553, granted to me, I have illustrated and described an attachment or mechanism for playing a 15 stringed instrument, in which are employed a plurality of vibratory spring hammers having their rear ends affixed to a support, and having their free headed ends extending over the strings, so arranged that, when each 20 spring is depressed, it engages a stop arranged in its path, and its head is caused either to strike a string once or a number of times in rapid succession according to the length of time during which the spring is 25 depressed.

The present invention has for its object to provide an improved playing mechanism, which will have a greater durability, which will be easy to repair, and which will be 30 cheaper to construct, and furthermore one which will be capable of more rapid and accurate operation than that shown in my said patent.

On the accompanying drawings,—Figure 35 1 shows a zither equipped with my improved playing mechanism. Fig. 2 represents an enlarged section on the line 2—2 of Fig. 1, showing one of the hammers and keys in normal position. Fig. 3 represents 40 a similar section with the key depressed to cause the vibration of the hammer. Fig. 4 shows another form of key, in which the front or finger-engaged end is integral with the rear or heavier end.

45 The instrument, to which the attachment is secured, is shown as a zither having the usual base 4 and sounding board 5, spaced apart by the usual frame including the hitch pin block 6 which forms the end of the body.

50 The melody strings 7 (of which two are shown for each tone) are illustrated as being sufficient in number for two diatonic octaves, although of course the number or arrangement is not material. The chord strings are arranged in groups as indicated

at 8. The instrument thus far described is like the well known "Columbia" zither which has been on the market for a number of years.

To secure varied musical effects, it is desirable to employ a playing attachment, in which the hammers are capable of striking the string a single blow to produce a full clear note, and also of striking the string a number of times in quick succession to produce a sustained tone like that produced by a mandolin. This is obtained by the employment of vibratory spring hammers each having a head of sufficient weight so that the momentum imparted thereto by moving 60 the spring will cause it to vibrate rapidly and impinge against the string at each vibration. Hence I employ such hammers, each consisting of a relatively thin steel spring 9 to which is attached at its free end 65 a head 10. This head I preferably form of lead cast directly on the end of the spring, as the tone produced by the impingement of the lead upon the string is sweet and pleasing. But, where a relatively long flexible 70 spring is employed for this purpose, it is difficult to secure accuracy in playing, for the reason that force is applied frequently in an oblique direction to the hammers which tends to force the heads sidewise and cause 75 them to impinge upon the wrong strings. To obviate this difficulty, I employ short springs with heads of sufficient weight to cause a proper vibration, and pivot the springs upon a pivot bar 11 so that it is not 80 necessary to bend the springs to depress them. To this end, each spring is rigidly affixed to a weight or block 12, made of wood, lead or other suitable material, and the block, at what I may term its front end, 85 is apertured to receive the pivot at a point immediately adjacent the spring. The weights or blocks constitute parts of the keys, as will be explained.

The ends of the pivot bar are secured in 100 two blocks or standards 13 adjustably mounted upon supports 14 by screws 15 passing through slots 16.

The blocks 12, the standards 13, the supports 14 and the pivot rod 11 are all inclosed 105 within a boxlike casing, which may be formed separately and attached to the end of the instrument, so as to be bodily removable therefrom. Said casing may, for example, have end walls 17, 18, which over- 110

lap and are detachably secured to the sides of the instrument, a bottom wall 19, the under face of which is flush with the under face of the base 4, a rear wall 20, and an upper wall 21, which walls form an oblong box, the front (*i. e.*, away from the player) of which is open. The box covers the pin block, and obviates the use of the usual guard.

10 The blocks 12 are generally in the shape of a right angle triangle with one angle truncated, so that, when the blocks are at rest, one edge 12^a is vertical and the other edge 12^b is approximately horizontal. When 15 the hammer is depressed, as shown in Fig. 3, the edge 12^c is brought into horizontal position. The oscillatory movement of each block is limited by the upper and lower walls of the casing, and this for a purpose 20 to be explained. The spring of each hammer may be secured by suitable fastenings to the upper edge 12^c of a block, or it may be otherwise attached to the block in some convenient manner. The bar 11 extends 25 transversely of the strings and occupies a vertical plane beyond the ends of the effective portions of the strings.

The wall 21 serves three important functions. It serves as a rest upon which the 30 hand or wrist of the player may be placed, a guard for preventing interference with the action of the blocks, and a stop for limiting the movement of the blocks abruptly so as to cause the spring hammers to vibrate. 35 Its edge is beveled to facilitate the easy manipulation of the hammers.

To the under side of the wall 21 is secured a strip 22 of cushioning material such as 40 felt to deaden any sound consequent upon the impingement of a block thereagainst, and upon the bottom or lower wall 19 there is a strip 25 of felt or equivalent material 45 on which the blocks normally rest.

To each hammer is secured a non-resilient 45 finger-piece 23. This may be formed integrally with the block, as shown in Fig. 4, or, as shown in Figs. 2 and 3, it may be formed of a small piece of sheet metal bent around the spring and firmly clamped thereon upon 50 the block so that the key and block form a movable unit. The front end of each piece, when constructed as shown in Fig. 2, has an extension or tab 24 extending at an inclination to the spring to prevent the finger 55 pieces from slipping off longitudinally. The finger pieces project forwardly from under the wall 21 and are normally upwardly inclined so that the hammer head has a relatively long arcuate movement. The keys 60 (comprising the portions 23 to be engaged by the fingers, and the blocks 12) serve to pivot the hammers upon the bar 11, and also act as weights to restore the hammers to normal position when they are released.

65 They are limited in their oscillatory move-

ment by separated stops which consist of the cushion-shod walls 21 and 19. The wall 21 is so located that, when it is engaged by a block 12, the spring hammer is some distance away from its corresponding string, 70 as shown in full lines in Fig. 3. Hence, when the exposed portion of the key is depressed by the player, the hammer and block swing freely about the pivot bar, until the movement of the block is abruptly checked, 75 whereupon the inertia of the hammer causes it to continue its movement and impinge upon the string. If the key be immediately released, but one blow will be struck and the hammer will be returned to normal position. 80 But, if the player continues to hold the key depressed, the hammer will vibrate rapidly, as illustrated by dotted lines in Fig. 3, and strike the string a number of times.

Each key is pivoted between its ends upon 85 the pivot bar, and in referring to the "depression of the key" I mean of course to the depression of the front end or that portion 23 of the key which is on the same side of the pivot as the hammer, the heavier ends 90 being termed the rear ends for the sake of distinction.

As in the attachment disclosed in the Letters Patent hereinbefore described, I employ means for checking the vibration of the 95 hammers when released, such means comprising a cushion-shod bar 26. This bar consists of an elongated metallic strip, the longitudinal marginal portions 27 of which are doubled under to embrace and clamp a 100 layer 28 of felt or like material. A filler 29 of like material but less in width is disposed between the strip and the layer 28, so that the face of the latter projects beyond the marginal portions 27 and prevents their 105 being struck by the hammers. The bar as a whole is supported upon the ends of two springs 30 secured by suitable fastenings upon the inclined upper portions of the standards 13. 110

Between the blocks 12 I place washers 31 to separate them a slight distance.

The action, which I have herein described, responds to a delicate touch, and effects are obtained which are very pleasing to the ear. 115 By employing weights for restoring the hammers, I prevent an increasing resistance to pressure upon the keys, such as is incident to the use of springs, and I prevent the crystallizing action which causes the springs to 120 break after being use for some time.

The removal of the top wall 21 permits access to the blocks, and the entire action may be adjusted or removed by loosening or removing the screws 15. The hammers and 125 their attached blocks may be slipped off the pivot bar for the replacement or repair of any of them, and may be reassembled in any order, as they are all alike.

Of course it is not necessary that the cas- 130

ing or box should be removable from the body of the instrument, as it could be easily constructed as an integral part thereof.

It will be understood that various changes 5 may be made in the construction of the several parts without departing from the spirit and scope of the invention. If the rear portions of the keys be made of lead, they will be made correspondingly small.

Having thus explained the nature of my 10 said invention and described a way of making and using the same, although without attempting to set forth all of the forms in which it may be made or all of the modes 15 of its use, what I claim is:—

1. The combination with a stringed musical instrument, of a plurality of spring hammers each comprising a spring strip and a head therefor, a horizontal bar on which 20 said hammers are fulcrumed, a weight connected to each hammer and arranged in the rear of the said bar to hold the head of said hammer away from its corresponding string, a stop for arresting movement of each hammer toward the string whereby said head 25 is caused to vibrate, and a finger piece attached to each hammer and projecting on the opposite side of said bar from the weight and movable to cause the impingement of 30 the hammer upon its string.

2. The combination with a stringed musical instrument, of a plurality of non-resilient keys, a spring-hammer attached to and extending from one end of each key and 35 having a head on the free end thereof normally distant from its corresponding string, a bar on which said non-resilient keys are fulcrumed, each key having a portion between the pivot and the hammer head exposed 40 for manipulation by the player, and a stop in the path of movement of each key for arresting the movement of the key, when the latter is operated to move the hammer from its normal position toward its corresponding string, whereby the head is caused 45 to vibrate against the string.

3. The combination with a stringed musical instrument, of a plurality of non-resilient keys, a bar on which said keys are fulcrumed intermediate of their ends, a spring hammer extending from the front free end of each key, and a stop above the rear free ends of the keys to arrest the upward oscillatory movement thereof, whereupon the 50 momentum acquired by the head of the spring hammer causes it to vibrate against the string.

4. The combination with a stringed musical instrument, of a hand rest extending 55 transversely of the strings, a bar extending longitudinally of said hand rest, a plurality of non-resilient keys fulcrumed between their ends on said bar, the rear ends of said keys lying under said hand rest, and the 60 front ends projecting beyond said hand rest

and exposed for manipulation, spring hammers secured to and extending from the front ends of said keys, and a stop for arresting the upward movement of the rear ends of said keys whereby the hammers are 70 caused to vibrate.

5. The combination with a stringed musical instrument, of a plurality of non-resilient keys, a bar on which the keys may freely oscillate, a spring hammer carried by each 75 key, and a hand-rest overhanging the rear portions of said keys, a front portion of each key when at rest extending above the plane of said hand-rest for manipulation.

6. The combination with a stringed musical instrument, of a bar arranged transversely of the strings, a plurality of non-resilient keys fulcrumed between their ends on said bar, separated stops between which the rear free ends of said keys may oscillate, 85 and spring hammers projecting from the front ends of said keys and normally raised from the strings, and being moved into engagement with the strings by pressure applied to the front ends of said keys. 90

7. The combination with a stringed musical instrument, of a horizontal bar, a plurality of non-resilient keys fulcrumed between their ends on said bar, spring hammers carried by the front ends of said keys, 95 the rear ends of said keys being of sufficient weight to hold the hammers away from the strings in normal position, a hand rest arranged above the rear ends of said keys and forming a stop to limit the upward movement thereof, the front ends of said keys projecting beyond said hand rest for manipulation by a player. 100

8. The combination with a stringed musical instrument, of a plurality of spring 105 hammers projecting over the strings, a plurality of blocks or weights to each of which the rear end of one of the hammers is affixed, a horizontal bar on which the front ends of said blocks or weights are fulcrumed, whereby the hammers are held normally away from the strings, exposed finger pieces on said blocks projecting forwardly from the said bar for direct manipulation and depression by a player, and 110 a stop arranged to stop the movement of said blocks before the hammers engage the strings. 115

9. The combination with a zither, of a casing attached to the end thereof beyond 120 the strings and comprising upper and lower walls, a horizontal bar in said casing, a plurality of keys fulcrumed between their ends on said bar, the front ends of the said keys projecting out of the casing over the strings, 125 and the rear ends being weighted and being located in the casing and limited in movement thereby, and spring hammers attached to the front ends of the keys, and comprising springs and heads on the free ends 130

thereof, said spring hammers being normally elevated above the strings by the weighted rear ends of the keys, and being operated by pressure applied to the front 5 ends of the keys.

10. The combination with a stringed musical instrument, of a horizontal bar, a plurality of keys fulcrumed upon said bar, and having heavy rear portions, supports in 10 which said bar is mounted, spacers on the bar between said keys, spring hammers projecting from the front ends of the keys and normally held away from the strings by the heavy portions of said keys, and means for 15 arresting the movement of the keys when the front ends are moved toward the strings, whereby the hammers are caused to vibrate against the strings.

11. The combination with a stringed musical instrument, of a horizontal bar arranged transversely of the strings, a plurality of non-resilient keys fulcrumed on said bar, supports in which said bar is mounted, spring hammers projecting from 25 the ends of said keys, means for yieldingly holding each key with its spring hammer away from its corresponding string, and means for arresting the movement of the keys when the hammer-carrying ends thereof are moved toward the strings, whereby 30 the hammers are caused to vibrate against the strings.

12. The combination with a stringed musical instrument, of a horizontal bar arranged transversely of the strings, a series 35 of non-resilient keys fulcrumed between

their ends upon said bar, a spring hammer extending from one end of each key, a cross bar arranged over the other ends of the keys to form a stop to arrest the operative movement of said keys whereby said spring hammers are caused to vibrate against said strings. 40

13. The combination with a stringed musical instrument, of a series of non-resilient 45 keys mounted above said strings, means for pivotally supporting said keys, each key having a finger piece, a spring hammer projecting from each key on the same side of the pivot as the finger piece, and means for 50 arresting the movement of said keys toward the strings to cause the vibration of said hammers against the strings.

14. The combination with a stringed musical instrument, of a series of pivotally 55 mounted non-resilient keys extending longitudinally of the strings, means for pivotally supporting said keys, each key being provided with a finger piece, a spring hammer projecting from each key, each associated 60 finger piece and hammer being on the same side of the pivot for the key, and means for yieldingly holding said keys in normal position with the hammers thereof remote from the corresponding strings. 65

In testimony whereof I have affixed my signature, in presence of two witnesses.

HENRY C. MARX.
